UNITED STATES PATENT OFFICE.

WIRT S. QUIGLEY, OF ROCKAWAY PARK, NEW YORK.

OIL-BURNER.

1,104,386.

Specification of Letters Patent.

Patented July 21, 1914.

Application filed October 31, 1912. Serial No. 728,910.

To all whom it may concern:

Be it known that I, WIRT S. QUIGLEY, a citizen of the United States of America, residing at Rockaway Park, county of 5 Queens, State of New York, have invented certain new and useful Improvements in Oil-Burners, of which the following is a specification.

My invention relates to oil burning apparatus and comprises an improved form of spraying nozzle for use in such burners.

Attempts have heretofore been made to produce a burner for oil consuming furnaces in which the oil is sprayed into the combustion chamber by a mechanical atomizing action due to centrifugal force which separates a fine whirling stream of oil issuing from a nozzle under pressure into small globules or molecules. The difficulty with 20 this type of apparatus has been that the heat carbonized the oil in the jet apparatus and soon the fine opening from which the jet issued was choked with carbon and the device became inoperative.

25 I have overcome this difficulty by the present invention which comprises an efficient needling device combined with such jet producing apparatus whereby the fine discharge opening may be easily cleared of deposited material as often as is necessary.

The best form of apparatus embodying my invention at present known to me is illustrated in the accompanying sheet of drawings in which,

35 Figure 1 is a longitudinal section of the apparatus with parts broken away. Fig. 2, is a detailed side view of the needle operating apparatus, and Fig. 3 is a cross section on line 3, 3, of Fig. 1.

40 Throughout the drawings like reference characters indicate like parts.

1 is a metal tube having fitting 2, screwed into one end and spraying head 3, screwed into the other end. 4 is the oil inlet to said tube, 5 is a smaller tube in main tube 1, one end of which is forced into the central chamber 6, of head 3, while the other is forced into central bore 7, of fitting 8, (which is screwed into fitting 2) forming 50 an oil tight joint therewith.

The head 3, has a threaded button 9, separated from the head proper by annular groove 10, which annular groove forms an annular chamber when the button 9 is 55 screwed into tube 1, so as to bring head 3, up against the end of tube 1, as shown in

Fig. 1. This annular chamber is connected by fine holes 11 through button 9, with the interior of tube 1, and, by one or more holes 12, with the central chamber 6, the holes 12 being nearly tangential to the inner circumference of said chamber 6, or parallel to tangents thereto, and considerably offset from the center.

13 is the jet opening in the center of head 65 3, communicating with the center of chamber 6. The total area of cross section of holes 12 must be at least equal to or greater than, the area of cross section of jet opening 13.

A needle point 14, is set in the end of rod 15, in line with jet opening 13. Rod 15 extends through inner tube 5, through a stuffing box 16, in fitting 8, and into skeleton housing 17, to which it is fastened by set 75 screw 18. This housing 17 rotates on fitting 8, within the limits permitted by helical slot 19, in the housing, engaging radial pin 20, set in the fitting. 21, is a weighted crank fastened to housing 17, by set screw 22. 80

In operation, oil under high pressure is supplied through supply connection 4, passes through perforations 11 and 12, in head 3, and enters central chamber 6, in tangential streams of high velocity. This 5 gives a rapid whirling motion to the oil in chamber 6, and to the jet which issues from it through opening 13. Consequently the particles of oil forming the jet fly apart by centrifugal action into a spray as soon as 90 they are free from the restraining influence of the walls of jet opening 13, and form a combustible mixture with the surrounding air. This combustible mixture is ignited by the heat of the combustion chamber (not 95 shown) into which it is introduced. Whenever the checking of this combustion shows that the supply of oil is being reduced by filling up of the jet opening 13, a quarter turn of crank handle 21, will, by co-action 100 of slot 19 and pin 20, force housing 17, rod 15 and needle 14 forward so that the needle is projected into, and cleans, jet opening 13. On releasing the handle its weighted end causes it to drop down, automatically 105 withdrawing the needle from the jet opening and permitting the spraying device to resume full action.

The advantages of my invention arise from the fact that it is vastly more economical in power consumption to pump the small volume of oil under pressure necessary to 110

produce the whirling mechanical spray, than to pump the larger volume of air under the pressure necessary to produce an atomizing of the oil, as in the ordinary type of burner. The combination of the needling device with this mechanical atomizer makes it possible to use it continuously overcoming the disabling effect of the carbonized oil, which has heretofore rendered 10 such atomizers impracticable.

Having, therefore, described my invention, I claim:

An oil spraying device for use as an oil burner comprising in combination a tube 15 for supplying the oil, a nozzle therefor consisting of a head having a central bore and a fine perforation axially thereof, serving as a discharge orifice, an outer annular cut-

away portion and a series of perforations through the inner flange so formed and 20 through the shell left surrounding the central bore, the perforations through said shell being approximately tangential to the circumference of the bore and considerably larger in area of cross section than the before described discharge orifice, together with a tube and stuffing box closing the inner end of the axial bore, a needle mounted in said tube in line with the discharge orifice and means for manually projecting and 25 withdrawing said needle quickly through and from said discharge orifice.

WIRT S. QUIGLEY.
